UNITED STATES PATENT OFFICE.

GLEN B. SMITH, OF FORT WORTH, TEXAS.

AEROPLANE.

1,177,545.

Specification of Letters Patent. Patented Mar. 28, 1916.

Application filed January 21, 1915. Serial No. 3,424.

To all whom it may concern:

Be it known that I, GLEN B. SMITH, a citizen of the United States, residing at Fort Worth, in the county of Tarrant and State of Texas, have invented certain new and useful Improvements in Aeroplanes, of which the following is a specification.

My invention relates to aeroplanes or flying machines and more particularly to the fuselage for aeroplanes; and the object is to improve the construction of the fuselage for the purpose of securing double strength throughout the body and yet provide fuselage which will be light and durable and to construct the rear part so that there will be more wind surface in the altitude planes and also to provide an improved connection for the rudder.

Another object is to provide the rudder with direction levers for making the rudder safer and stronger.

Another object is to provide the landing gearing with air-cushions.

A further object is to provide a telescopic joint in the central part of the fuselage.

A further object is to provide sprocket gearing for the altitude planes so that there will be no chance for play.

Other objects and advantages will be fully explained in the following description and the invention will be more particularly pointed out in the claims.

Reference is had to the accompanying drawings which form a part of this application.

Figure 1 is a plan view of the aeroplane. Fig. 2 is a side elevation of the same. Fig. 3 is a detail view of the frame of the rudder. Fig. 4 is a vertical section of the aeroplane, taken on the line $y-y$ of Fig. 2, looking forward. Fig. 5 is a vertical section on the line $y-y$ of Fig. 2, looking backward. Fig. 6 is a front elevation of the aeroplane. Fig. 7 is a vertical section of the same, taken on the line $x-x$ of Fig. 2. Fig. 8 is a detail view on an enlarged scale of the connection of the rudder with the rear end of the fuselage. Fig. 9 is a detail plan view of one of the wings. Fig. 10 is a detail view of the gearing for operating the rudder. Fig. 11 is a longitudinal section of one of the air-cushion cylinders of the landing gearing.

Similar characters of reference are used to indicate the same parts throughout the several views.

The fuselage is larger toward the front

part than toward the rear. The front part has longitudinal bars arranged in pairs 1-1, 2-2, 3-3, and a single central bar 4 at the bottom. The bars 1-1 and 3-3 on each side terminate substantially at the central parts with long feather ends which engage the ends of bars 5 which extend to the rear end of the machine. The bars 2 also terminate with feather ends against the bars 5 at the central part of the frame, the ends of the bars 5 being telescoped in between the feather ends of the bars 1-1, 2-2, and 3-3, and secured to these bars in any suitable manner, as by rivets 64. The rear part of the fuselage has only four longitudinal bars, the bars 5-5 and bars 6 and 11. The bar 6 has a telescopic joint with bar 4 at the central part of the machine. In the rear part of the fuselage, the longitudinal bars are braced by horizontal bars 7 and vertical bars 8 which are gained into each other. The fuselage is further braced throughout its length by curved braces 9 which extend entirely around the body. The covering 10 is placed on the outside of the curved braces 9. In Figs. 1 and 2, the covering 10 is omitted for clearness in illustration. For the same reason only a few of the curved braces 9 are shown. At the rear end the bars 5 are attached to a horizontal bar 16 which is connected to a piece 12 and rigidly braced. The rudder 13 is pivotally connected to the upright 12 by a ball bearing connection at 14. The rudder is constructed preferably of a wooden frame shown in Fig. 3, all the parts thereof being wood except the thin steel cross-bars 15. The bar 12 and the bar 16 may be gained into each other. The bars 6 and 11 are attached to the upright 12. The bar 11 is attached to a bar 17 which extends forward of the telescopic joint in the central part of the machine. The bars 11 and 17 and the bars 4 and 6 are cut to form feather ends and these feather ends lap on each other so that there is no enlargement to form continuous bars. The lapped ends are connected to each other in any suitable manner. The interior bracing of the fuselage at the central part consists of bars 18 so connected to the longitudinal bars as to form a quadrangular brace. Forward of the center of the fuselage, the principal bracing consists of bars 19 which form an upright quadrangular brace, there being a quadrangular brace wherever needed. The forward

part of the frame is further braced by the bars 20 and a strut 21, resting against the bar 4. The same form of bars 20 and struts 21 are used to brace the bars 2.

5 A fin 22 is vertically mounted on the rear part of the machine and has a triangular form. The rudder 13 and the fin 22 are connected by a ball bearing connection at 23, which is the same in construction as that shown in Fig. 8, hereinafter explained.

10 A vertical shaft 24 is supported in brackets 25 which are secured to the tail piece 12. Ball bearing cups 26 are mounted above and below the brackets 25. Caps 27 prevent the removal of the balls from the cups 26. The bearing is connected to the rudder by angle brackets 28 which are attached to the rudder and through which the shaft 24 passes and the shaft 24 is secured in place by the nuts 29. The rudder is thus connected to the ball bearings by the brackets 28. The rudder is provided with steering arms 30 projecting horizontally therefrom for steering purposes. Cables 31 are attached to the arms 30 and extended forward to the steering wheel 53, at which point suitable levers are provided for turning the rudder by means of the cables 31. Skids 33 are attached to the underside of the rear end of the fuselage. The skids are made rigid with braces 34.

15 The aeroplane is provided with wings or planes 35 of ordinary construction and these planes are provided with ailerons 38. Wings 35 or planes 37 are provided for the front part of the aeroplane and these planes may be of any approved construction and are provided with ailerons 38.

20 In addition to the braces above described, interior braces are provided to brace the fuselage between each set of braces 7 and 8 in the rear part of fuselage and between the braces 18 of the front part and these braces consist of wire or cables 39 run diagonally from the upper to the lower part and from side to side wherever needed.

25 The landing gearing includes wheels 40 which are carried in bearings on forks 41 and 42. The forks are hinged at 43 and the upper ends of the forks 41 and 42 are formed into plungers which enter air-cushion tubes 44 and these tubes 44 are hinged to the lower front part of the fuselage. When the machine is landing, the plungers 45 on the forks will be forced into the tubes 44 against air, making an elastic cushion for absorbing the shock of the machine striking the ground. In order that the elements of the landing gearing may be returned to their 30 normal positions, a spiral spring 59 is mounted in the cylinder 44 and the cylinder is provided with a pet cock 60 for releasing the air in the cylinder after operation.

35 At the forward end of the fuselage, the longitudinal bars 1-1, 2-2, and 3-3 are

attached to the respective uprights 45. The uprights 45 are braced by suitable cross-bars 46 and diagonal braces 47. An opening is provided in the top of the front part of the machine and an elliptical brace 48 surrounds the opening and forms a frame for the opening or door. A seat 49 is mounted on braces 50 which are attached to bars 51 which are attached to the bars 19. A canopy 52 is mounted over the door. The steering wheel 53 is mounted on a standard 54. A sprocket wheel 55 is attached to the steering wheel 53 and a sprocket chain 56 is mounted on the sprocket wheel 55. This sprocket chain is connected to the cables 31 which run under pulley wheels or idlers 57 and back to the levers 30 of the rudder 13.

40 Planes 35 and 37 are shown attached to the aeroplane, and these planes are of the ordinary construction and will not be set forth in detail. They are omitted from Fig. 2 for clearness in illustration, except the inner frame piece 61 which is operated by a walking beam 62. The walking beam 62 operates the planes on opposite sides of 45 the aeroplane by means of suitable cables 63 which are operated from the standard 54.

45 A motor 57 of approved design is used to drive the propeller 58. The motor and the propeller are located in the front part 50 of the machine to be operated by the aeronaut. As these elements form no part of my invention, they will not be set forth in detail.

50 What I claim is,—

1. An aeroplane having a fuselage composed of a plurality of side longitudinal bars for the front part thereof terminating at the central part of the aeroplane with relatively long feather ends and a pair of 105 side longitudinal bars for the rear part of the aeroplane terminating at the central part of the machine with relatively long feather ends and connected to said first mentioned feather ends, and top and bottom 110 longitudinal bars attached to the front and rear parts of the aeroplane and terminating with relatively long feather ends at the central part of the aeroplane, and means for attaching the feather ends of the said front 115 bars to the feather ends of the said rear bars.

2. An aeroplane having a fuselage in two parts joined together, each part having bars terminating with relatively long feather 120 ends and the feather ends of the two parts being telescoped together, means attaching the feather ends together, quadrangular braces spacing said bars to operative position, and cables for bracing said bars and 125 said quadrangular braces.

3. An aeroplane having a fuselage in two parts composed of longitudinal bars, said bars having relatively long feather ends telescoped together to form a juncture of 130

the two parts, means securing the feather ends of the bars together, said fuselage having a general cylindrical form, and means for bracing said bars on the inside of the

5 fuselage.

4. An aeroplane having a fuselage in two parts, the parts being joined at the central portion of the machine and each part consisting of longitudinal bars arranged in a

10 general cylindrical form and the bars termin-

nating with relatively long feather ends to be telescoped together at the central portion of the machine to form said joint.

In testimony whereof, I set my hand in the presence of two witnesses, this 17th ¹⁵ day of September, 1914.

GLEN B. SMITH.
